UNITED STATES PATENT OFFICE.

ANTONIO C. GARCIA, OF ERMITA, MANILA, PHILIPPINE ISLANDS.

HORSE-RACE GAME.

Application filed February 12, 1924. Serial No. 692,413.

To all whom it may concern:

Be it known that I, ANTONIO C. GARCIA, a citizen of the United States, residing at Ermita, Manila, Philippine Islands, have invented certain new and useful Improvements in Horse-Race Games, of which the following is a specification.

The present invention has to do with certain improvements in games of chance and the like. The game of chance herein disclosed is one in which a number of figures, such as miniature imitation race horses, are intended for operation around a track way in such a manner that they can be raced or competed against one-another. More particularly in this connection, the invention relates to certain improvements in machines of this class for controlling by chance the winner of the race between the figures of the miniature imitation race horses.

More particularly the features of the invention have to do with a machine so designed and controlled as to be operable electrically as distinguished from constructions in which the improvements of the individual units are occasioned mechanically.

One of the features of the invention has to do with the provision of an arrangement in which any suitable number of figures or units, as, for example 8, may be used, each being under the control or operation of an electric circuit so that normally the figures would move about the track so as to reach the goal or finish line simultaneously, means being provided whereby one of the circuits may be shorted so that the figure controlled by said circuit will move sufficiently faster than the remaining figures so as to win the race.

Other objects and uses of the invention will appear from a detailed description of the same which consist in the features of construction and combination of parts hereinafter described and claimed.

In the drawings:

Figure 1 is a plan view of a completely assembled machine embodying the features of the present invention;

Figure 2 is a vertical section through a portion of the race track thereof;

Figure 3 is a side elevation, partly in section of one of the cars;

Figure 4 is a top plan view thereof;

Figure 5 is an elevation of the chance-controlled circuit closer, a portion thereof

being broken away to show the interior construction;

Figure 6 is a transverse section therethrough taken on the line 6—6 of Figure 5 looking in the direction of the arrow; 60

Figure 7 is a similar view taken on the line 7—7 of Figure 5 looking in the direction of the arrows; and

Figure 8 is a diagram showing the wiring used with the machine. 65

Referring to the drawing in detail it will be seen that A designates the base board which may be of any desired formation but is preferably rectangular in shape as is illustrated in Figure 1 and of sufficient strength 70 to support the apparatus to be placed thereon. A miniature race track or hippodrome B is mounted on the board A the detailed structure thereof being illustrated to advantage in Figures 2, 3 and 4. A rheostat 75 housing C is mounted along one side of the board, a chance controlled circuit closing D is disposed at one end thereof and a pair of switches E and F are disposed at the other end thereof. The relative positions of the 80 various parts thus far described may be varied as desired. The present illustration being illustrative of a compact embodiment of the game apparatus.

The race track is built upon the base 85 board A and consists of a plurality of ports 1 projecting upwardly from the board A for holding the track proper 2 in spaced relation above said board A. The track proper 2 is in the form of a plate the general contour of which is an imitation to the usual formation of a race track as indicated to advantage in Figure 1. Suitable sides 3 close the space between the track proper 2 and the board A. The track proper 2 is 90 provided with a plurality of concentric slots 4 which are equally spaced from each other and represent the pairs of racing figures or units indicated at 5. Under each slot 4, on the board A there is arranged a track for receiving the car or carriage supporting the figure or unit associated with the slot. Each track consists of a pair of rails 7 and a third rail 8 disposed therebetween. A groove 9 is provided in the board A adjacent each 95 rail 7. Associated with each track and slot 4 is a car or carriage indicated generally by the letter G. Each car includes a frame 10 substantially rectangular in formation supported on flange wheels 11 adapted to move 110

on the rail 7 of the tracks. The wheels 11 are mounted on crank axles 12. A bracket 13 is mounted on cranks of the crank axles 12 so that upon operation of the car the bracket 13 will have a circular movement. A standard 14 rises from each bracket 13 being adjustably held therein by means of a set screw 15 extending transversely through a sleeve 16 which receives the standard and is formed integrally or otherwise fixedly attached to the bracket 13. The standard 14 projects through the slot 4 with which the car is associated. The figure or unit 5 in the form of a miniature race horse is mounted on the standard 14 and thus as the car moves about the track the miniature figure will also move and give the appearance of a galloping race horse. A suitable motor is associated with each car G and may be of any conventional construction for rotating the wheels 11. These motors receive their motive force from the plows 18 which are always in engagement with the third rails 8.

Attention is now called to the chance-controlled circuit closing device D illustrated to advantage in Figures 5 to 7 inclusive. This device is formed from a stationary member H and a rotatable member I. The stationary member H is provided with a plurality of blocks 20 having openings 21 therein for the reception of suitable electric conductors. A container 22 of insulating material is mounted on each block 20. The containers 22 and the blocks 20 are housed in a suitable casing 23. Each container 22 is provided with a bottom contact 24 and a side contact 25 and a certain amount of mercury is carried in each container, the level of such mercury being such that normally a circuit containing the contacts 24 and 25 would be open. A plurality of sleeves 27 project upwardly from the casing 23 one communicating with each of the container 22. A plunger 28 is movable in each container being guided by the upper restricted portion thereof and has a stem projected upwardly therefrom into the corresponding sleeve 27 and terminates in a head 29 and a spring 30 is disposed between the head 29 and the bottom of the sleeve so as to normally hold the plunger 28 in a raised position out of the mercury in the container so that the level of the mercury will be normally at its lowest point that is not in engagement with contact 25. The upper end of each tube or sleeve 27 is flared as at 32 so as to form a receptacle immediately below the rotary member I. A standard 33 projects centrally upwardly from the stationary member for receiving the rotary member I. This rotary member consists of a casing 34 having a compartment 35 with a dome-shaped bottom 36. The casing 34 is provided with an entrance opening 37 preferably at its uppermost point

and at the edge of the dome-shaped bottom 36 is provided with an alley-way 38 having openings 39 therein which register with similar openings in the bottom partition 40 which is utilized for strengthening the rotary member. Thus it will be seen that a ball 41 or the like may be placed in the entrance opening 37 after the rotary member I has been placed in motion and will roll to the edge of the dome bottom 32 so as to pass through one of the openings 39 and fall into one of the receiving compartments 32 and thus be guided into the corresponding tube or sleeve 28 so as to rest on the head 29 of the stem therein thus compressing the spring 30 and forcing the plunger 28 into the mercury of the container 22 thereby raising the level of this mercury and electrically connecting contacts 25 and 24 for a purpose to be hereinafter set forth.

From the above description it is thought that the operation of the apparatus may now be clearly understood by referring to the diagram shown in Figure 8 wherein is disclosed a transformer 50 for connecting the leads 51 and 52, the switch F being disposed in the lead 51. A wire 53 is connected to the lead 52 and in turn is connected with a plurality of wires 54 in the present instance eight in number corresponding to the eight tracks of the race track. In each wire 54 there is disposed an adjustable or variable rheostat 55. The wires 54 are connected to the wires 56 which communicate with the third rails 8. The rails 7 are connected by wires 57 to a wire 58 which is connected to the lead 51 by a wire 59. Thus it will be seen that by closing switch F the current will pass through the lead 52, wire 53, rheostats 55, wires 54, wires 56, third rails 8, wires 57, wire 58 and wire 59 to the lead 51. By proper adjustment of the rheostats 55 it will be seen that the speed of the motors in the cars may be regulated so that normally the figures or racing units 5 will arrive at the finish line at the same time. The lead 52 is continued or connected to a wire 60 which is connected to each of the contacts 55 by wires 61. The switch E is disposed in the wire 60 between its first contact with the wires 61 and its contact with the lead 52. The contacts 24 are connected to the wires 56 by wires 62. Supposing that the racing figures or units 5 are lined up as shown in Figure 1 at the starting line and the switch F is closed. It will be seen that the figures will race about the track at different rates of speed so as to finish simultaneously with each other, of course, presuming that the rheostats 55 have been properly adjusted for this purpose. If, however, the chance-controlled device has been used prior to the closing of switch F it will be seen that one of the circuits of the motors of the carriages supporting the rac-

ing units will be short through the circuits including the contacts 24 and 25 and that therefore more electric motive force will be attracted to the motor in this circuit since the current will not pass through the rheostat thereof and this figure will win the race.

It is evident that the game may be played in other ways and suitable rules may be adopted as to when the chance-controlled circuit closing device is to be operated or when the switch E is to be closed but at any rate the same principle will be involved.

While I have herein shown and described a single embodiment of the features of my invention, still I do not limit myself to the same except as I may do so in the claims.

What is claimed is:

1. In a game apparatus of the class described, the combination with a drum having an apertured alley arranged thereabout, of a device including a plurality of tubes for rotatably receiving the drum whereby said drum may be placed in rotation and a ball inserted therein so as to drop into one of the tubes, each tube including a circuit closer actuated by the weight of said ball, each circuit closer including a container, mercury in the container, a pair of contacts one at the bottom thereof and another at the side thereof, the side contact being normally out of engagement with the mercury, and means in the container depressible by the weight of the ball so as to raise the level of the mercury so as to close a circuit between the two contacts.

2. In a game apparatus of the class described, the combination with a drum having an apertured alley arranged there-

about, of a device including a plurality of tubes for rotatably receiving the drum whereby said drum may be placed in rotation and a ball inserted therein so as to drop into one of the tubes, each tube including a circuit closer actuated by the weight of the ball, each circuit closer including a container, mercury in the container, a pair of spaced contacts one at the bottom of the container and the other at the side thereof, the side contact being normally out of engagement with the mercury, a plunger in each container for receiving the ball so as to be sunk downwardly in the mercury and raise the level thereof to close a circuit between the two contacts.

3. In a game apparatus of the class described, the combination with a drum having an apertured alley arranged thereabout, of a device including a plurality of tubes for rotatably receiving the drum whereby said drum may be placed in rotation and a ball inserted therein so as to drop into one of the tubes, each tube including a circuit closer actuated by the weight of the ball, each circuit closer including a container, mercury in the container, a pair of spaced contacts one at the bottom of the container and the other at the side thereof, the side contact being normally out of engagement with the mercury, a plunger in each container for receiving the ball so as to be sunk downwardly in the mercury and raise the level thereof to close a circuit between the two contacts, and a spring associated with the plunger to normally hold it in a raised position.

In testimony whereof I affix my signature.
ANTONIO C. GARCIA.
